UNITED STATES PATENT OFFICE.

CHESTER E. SHULER, OF CLIFTON, KANSAS.

MUSIC-LEAF TURNER.

SPECIFICATION forming part of Letters Patent No. 581,041, dated April 20, 1897.

Application filed July 6, 1896. Serial No. 598,190. (No model.)

To all whom it may concern:

Be it known that I, CHESTER E. SHULER, a citizen of the United States, residing at Clifton, in the county of Washington and State 5 of Kansas, have invented a new and useful Music-Leaf Turner, of which the following is a specification.

My invention relates to a music-leaf turner, and has for its object to provide a simple 10 and efficient construction and arrangement of parts whereby the leaves of a book or sheet-music may be turned successively in either direction by the depression of a key carried by a suitable operating-lever and adapted to 15 be arranged within convenient reach of the performer.

Further objects and advantages of this invention will appear in the following description, and the novel features thereof will be 20 particularly pointed out in the appended claims.

Figure 1 is a perspective view of a music-leaf turner constructed in accordance with my invention. Fig. 2 is a vertical section of 25 the same. Fig. 3 is a detail view of the lower operating-disk and catch. Fig. 4 is a detail horizontal section taken below and contiguous to the plane of the central rest, showing the spring-actuated detents for engaging the 30 turning-arms. Fig. 5 is a detail view in perspective of the disks, on an enlarged scale, showing turning-arms and the catches in operative relation therewith. Figs. 6, 7, 8, and 35 9 are detail diagrammatic views of the disks and arms, showing the successive relative positions of the parts.

Similar numerals of reference indicate corresponding parts in all the figures of the drawings.

1 designates a rack provided with a central 40 rest 2 and terminal spring holding-arms 3, and beneath said central rest are mounted the coaxial turning-arms 4, provided with terminal clips 5. Arranged below said rest 45 and respectively upon opposite sides of the common horizontal plane of the turning-arms are the upper and lower operating-disks 6 and 7, provided, respectively, with peripheral catches 8 and 9 to engage lateral studs or projections 10 and 11 on the turning-arms, said 50 studs projecting, respectively, over the peripheries of the operating-disks in the paths

of the catches, which are located, respectively, on the under surface of disk 6 and the upper surface of disk 7.

55

Connected with the operating-disks are means for turning the same in opposite directions, and the catches, which are adapted to engage the shoulders or projections on the turning-arms when the disks are moved, 60 respectively, in opposite directions, (said catches being mounted to project in opposite directions,) consist of spring-extended pivotal tongues 12, having terminal rounded extensions 13, which prevent the engagement of 65 the extremity of the tongue with any but the last turning-arm in the direction of movement of the disk. In other words, if the turning-arms are arranged at the right of the rack and the upper operating-disk is moved to turn 70 a leaf the end of the tongue carried by said disk is held out of engagement with the turning-arms, by the contact of its rounded extension with the lateral studs or projections on said arms, until the uppermost or foremost 75 turning-arm is reached, when said rounded extension being released by having passed said foremost turning-arm the catch is advanced by its actuating-spring 14 to bring the extremity of the tongue in engagement 80 with said stud or projection. By this arrangement only the single succeeding turning-arm can be operated, and hence the leaves may be turned successively by an alternate movement of either operating-disk in opposite directions. The turning-arms are held in either 85 position by means of holding-springs 15 and 16, located, respectively, upon opposite sides of the operating-disks.

The disks are normally held with their 90 catches in position for engagement with the studs or projections on the turning-arms by means of return-springs 17, which are fixed at one end to the disks and at the other end to the fixed spindle 18, upon which said disks, 95 in common with the turning-arms, are mounted, and in the construction illustrated the means employed for turning the disks in the opposite direction or in opposition to the tension of their return-springs to actuate the 100 turning-arms consist of key-levers 19 and 20, flexibly connected, respectively, as by cords 21 and 22, with suitable guide-pins 23 on the disks, said pins being arranged in circular

series around the springs to hold the cords out of contact therewith, and the cords being coiled around said pins in the opposite direction to that in which the springs, respectively, 5 are wound. The intermediate portions of the flexible connections traverse direction-pulleys 24, whereby when a key-lever is depressed the disk connected therewith is turned through an arc of approximately a 10 semicircle to move one of the turning-arms from a position at one side of the rack to a corresponding position at the opposite side. Each key is thus connected with a disk.

In order to adapt the improved rack for 15 attachment to the desk of a musical instrument and hold the same firmly in position, I employ a bottom ledge or rest 25, adapted to bear upon the book-rest 26, which is shown in dotted lines in Fig. 2, and a slide 27, terminally mounted in guides 28, formed in parallel upright bars 29 on the rack and having a clothed lip 30 to engage the upper bead of the desk. Said slide is secured at the desired adjustment by means of a threaded stem 31, 25 engaged by a thumb-nut 32, which bears upon a fixed cross-bar 33 between said uprights 29.

From the above description it will be seen that inasmuch as the turning-arms, which are mounted upon a common axis, are provided 30 at a common distance from their axis with the studs or projections for engagement by the catches on the operating-disks said arms are interchangeable and may be replaced at a small cost in case of breakage or other injury. I am enabled to construct the turning-arms with projections arranged at a common distance from the axis by reason of shaping the trip extension 13 with a bow which extends outwardly beyond the extremity of the 35 catch. This carries the extremity of the tongue inwardly out of reach of the studs or projections until all but the foremost turning-arm have been passed.

The selection by the catches of the foremost 40 stud or projection, or that which is carried by the terminal arm of a series, in either of the adjusted positions of the arms is due to the fact that as a disk is turned to cause the operation of a turning-arm the bowed extension 45 13, which is carried by the catch on said disk, glides along the inner sides or edges of the studs or projections and is thereby held repressed against the tension of the actuating-spring of the catch until said extension has 50 passed the stud or projection of the terminal turning-arm. As soon as this extension has passed this terminal stud the catch is returned to its normal or extended position by its actuating-spring and thereby is arranged 55 with its extremity in position to engage said stud or projection of the terminal arm. The extension or outward movement of the catch cannot occur until after the bowed extension 60 has passed the stud or projection of the terminal arm, and when thus extended the extremity of the catch is in advance of all of

the studs or projections except that which is carried by the terminal arm. Hence the continued rotation of the disk causes the terminal arm to be advanced and swung therewith to the opposite adjusted position. 70

Various changes in the form, proportion, and the minor details of construction may be resorted to without departing from the spirit or sacrificing any of the advantages of this 75 invention.

Having described my invention, what I claim is—

1. In a music-leaf turner, the combination with a rack, of coaxial interchangeable turning-arms having studs or projections spaced at a common distance from their common axis, operating-disks provided respectively with oppositely-extending yielding catches to engage said studs or projections of the turning-arms, and means carried by each catch for holding the same repressed until the engaging portion of the catch reaches the foremost stud or projection, substantially as 80 specified. 85

2. In a music-leaf turner, the combination of coaxial turning-arms arranged to swing in a common plane and each provided with upper and lower oppositely-extending studs or projections spaced at a common distance 95 from the common axis of the arms, operating-disks mounted respectively above and below the plane of and coaxially with the turning-arms, a selecting peripheral catch on each disk to engage the studs or projections of the 100 foremost arms in either adjusted position of the latter, springs for returning the disks in opposite directions, and means for moving the disks in opposition to the tension of their return-springs, substantially as specified. 105

3. In a music-leaf turner, the combination with a rack, of turning-arms having studs or projections arranged at a uniform distance from the common axis of the arms, operating-disks mounted coaxially with and respectively 110 above and below the plane of the arms, means for turning the disks in opposite directions, and oppositely-disposed catches on the operating-disks, each consisting of a spring-extended tongue adapted to terminally engage 115 the studs or projections on the turning-arms, and a curved extension 13 bowed outwardly beyond the extremity of the tongue for contact with the studs or projections to hold the extremity of the tongue out of engagement 120 with the studs or projections until the bowed extension has passed that of the terminal or foremost turning-arm of a series when the tongue springs outward to engage said stud of the terminal arm, substantially as specified. 125

In testimony that I claim the foregoing as my own I have hereto affixed my signature in the presence of two witnesses.

CHESTER E. SHULER.
